(57) **CLAIM**

The ornamental design for a hat, as shown and described.

DESCRIPTION

FIG. 1 is a perspective view of a hat;

FIG. 2 is a back view thereof;

FIG. 3 is a front view thereof;

FIG. 4 is a right-side view thereof;

FIG. 5 is a left-side view thereof;

FIG. 6 is a top view thereof; and,

FIG. 7 is a bottom view thereof.

The broken lines showing the brim and closure strap depict portions of the article and form no part of the claim. The singular lines of broken lines crossing claimed surfaces depict portions of the article and form no part of the claim.

1 Claim, 6 Drawing Sheets
